UNITED STATES PATENT OFFICE

116,273

DESIGN FOR A COMBINED APPLE SLICER AND CORER

Theodore William Moore, Riverside, Conn.

Application January 24, 1939, Serial No. 82,566

Term of patent 3½ years

To all whom it may concern:

Be it known that I, Theodore W. Moore, a citizen of the United States, residing at Riverside, in the county of Fairfield and State of Connecticut, have invented a new, original, and ornamental Design for a Combined Apple Slicer and Corer, of which the following is a specification, reference being had to the accompanying drawing, forming part thereof.

I claim:

The ornamental design for a combined apple slicer and corer, as shown.

THEODORE WILLIAM MOORE.
